WIRING TERMINAL CONNECTION FOR
ELECTRICAL WIRING DEVICES

Harvey Hubbell, Long Hill, Conn.

Application January 10, 1947, Serial No. 721,198

3 Claims. (Cl. 173—259)

1

This invention relates to electrical wiring devices, such, for example, as switches, receptacles and the like, and more particularly to the terminal connections for such devices, and has for an object to provide an improved terminal connection for such devices.

Another object is to provide a terminal connection for such devices which permits both front and back wiring of a lead wire to the terminal.

A further object is to provide a wiring terminal in which it is not necessary to wrap the lead wire around the binding screw in connecting it to the terminal.

A still further object is to provide a terminal in which the bared end portion of a lead wire may be inserted in the terminal while the binding screw is retracted and then clamped by merely tightening the screw.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of an electrical switch showing one form of my improved wiring terminal connection applied thereto;

Fig. 2 is a side view thereof looking toward the bottom of Fig. 1 and with parts broken away to more clearly show the construction;

Fig. 3 is a section on an enlarged scale showing a somewhat different construction of wiring terminal;

Fig. 4 is a view looking toward the bottom of Fig. 3 with the lower member of the body removed and showing the terminal on a somewhat larger scale, the view being taken substantially on the plane of the line 4—4 of Fig. 3;

Fig. 5 is a bottom plan view of a portion of the upper part of the body showing the recess in which the terminal is mounted;

Fig. 6 is a vertical section through this recess substantially on the line 6—6 of Fig. 5;

Fig. 7 is a section through the bottom section of the body, and

Fig. 8 is a view similar to Fig. 3 showing another somewhat modified construction.

In the drawings the terminal is shown as applied to a switch construction, but this is used merely by way of example, as the terminal connection is equally adapted for use in other electrical wiring devices, such, for example, as re-

2

ceptacles and the like, or any other electrical wiring device for which it is applicable.

In the form of the device shown in Figs. 1 and 2, the terminal connection is shown as applied to a switch mounted in a body of insulating material comprising a main portion 10 and a front portion 11, the portion 10 being provided with a chamber 12 in which the switch mechanism is mounted, including the movable switch member 13 operated by a toggle lever 14 and movable to and from a stationary contact 15. The section or portion 11 of the body forms a cover portion enclosing the open front side of the chamber 12 and is secured to the main body portion by any suitable means, such as the usual screws 16, passing through the body, and may be mounted in the usual wall outlet box or similar mounting by means of the yoke 17, also secured to the body by the screws 16 being threaded into it.

At the front side and at the opposite ends the body is provided with recesses 18 on the bottom surface of which are mounted the terminal connections 19. These each comprise a base portion 20, in this particular case in the form of a metal plate, secured to the body by screws 21 extending through the body and threaded into these plates. Each plate carries the usual type of binding post screw 22 threaded into the base portion, and including a shank 23 extending rearwardly from the base 20. At the inner edge of the base portion 20 is the stationary contact 15, either forming an integral part of the base portion or comprising a separate element secured to the base portion.

Rearwardly or under the base portion 20 there is provided an inclined lead wire supporting surface arranged to cooperate with the shank of the binding screw to clamp and secure the bared end of a lead wire to the device. This inclined surface may be provided on a wall of the insulating body or on a wall connected to the base portion in which the clamping screw is mounted. In the arrangement of Fig. 2 this inclined surface is on the insulating body. In this case the rear member 10 is provided with an inclined wall or surface 24 located at one side of and adjacent the shank 23 of the screw, and the body is provided with an opening 25 leading to this surface for insertion of the bared end 26 of the lead wire of conductor 27. This inclined surface 24 is located at one side of and adjacent the shank of the screw and is inclined to the axis of the shank, as shown in Fig. 2, 55 so that when the bared end 26 of the lead wire

is inserted between this surface and the shank of the screw, it may be clamped between the shank and the surface, the inclined surface forming a supporting surface for the wire, while the wire is clamped by the shank of the screw on the opposite side of the wire. In making the connection, the bared portion 26 of the wire may be inserted through the opening 25 as shown at the right hand end of Fig. 2, to a position between the shank of the screw and the inclined surface 24, when the screw is retracted. Then the screw is threaded downwardly to clamp its inner free end portion against the bared wire, as shown in Fig. 2. This securely clamps the bared wire between the shank of the screw and the inclined surface 24, securely clamping the wire and making a very effective electrical connection, and it will be seen this connection can be made without winding the bare portion of the wire around the clamping screw under the head of the screw, as in the usual terminal connection, although the wire may be so connected if desired.

As the material of the body 18 is usually made of some type of molded insulating material, it might have a tendency to crack under the pressure of the screw in clamping the wire. To form a reinforcement to reduce the strain on this material the base portion 20 of the terminal may be extended over the inclined wall 24 and provided with an opening 28 in substantial alignment with the surface, so that the free end portion of the wire is passed through and seats in this opening, as shown at 29. With this arrangement, part of the strain is carried by the metal base portion 20 of the terminal, relieving the pressure on the molded material of the body. It will be seen from this arrangement that the lead wire may be inserted from the back of the body or wiring device and clamped by merely setting the clamping screw, the screw shank together with the inclined surface 24 having a wedging action on the bared portion of the wire, which will effectively clamp it and prevent its being drawn out of the wiring device. However, with this arrangement the bared wire may be inserted from the front, as shown at the left hand of Fig. 2. That is, the bared portion 26a of the wire may be inserted from the front through the opening 28 in the base portion 20 of the terminal, to lie against the inclined surface 24 at one side of the shank of the binding screw, and may be clamped the same as in the arrangement at the right of Fig. 2. Therefore, it will be clear that in this arrangement both back and front wiring is provided without the necessity of looping or wrapping the wire under the head of the screw, but in any case the wire may be so looped and clamped if desired.

In the modification shown in Figs. 3 to 7, the insulating body comprises the two sections including the rear section 30 and the forward section 31, which together form the chamber 32 for the switch elements, only one of which, the stationary contact 33, is shown. The front portion 31 of this insulating body is provided with a recess 34 opening through the rear wall thereof and also passing through the section so as to be open at the front. At the opposite ends of the recess it is provided with grooves 35 having inclined bottom walls 36. Mounted in this recess is the wiring terminal comprising in this case a base portion 37 corresponding generally with the base portion 20 of the first form, and into this base portion is threaded the binding screw 38 including the shank

39 extending into and rearwardly from the base portion. At opposite side edges of the base portion are side walls 40 which are arranged at substantially right angles to the base portion and have inclined side edges 41 which, when the terminal is seated in the recess 34, seat on the inclined bottom walls 36 of the grooves 35 and prevent the terminal from passing through the front open side of the recess, and the terminal is retained in the recess by the body section 30, which closes the rear open side of the recess. The terminal also includes the inner wall 42 also bent up from one edge of the base portion, and the terminal contact 33 is connected to this wall.

Opposite to this wall 42 and between the side walls 40 is a supporting wall 43 bent downwardly or rearwardly from the edge of the base portion 37, and providing a laterally curved inclined supporting wall 44 at one side of and adjacent the shank 39 of the terminal screw. This wall and the surface are inclined to the axis of the screw the same as is the surface 24 of the form of Figs. 1 and 2, and forms a supporting surface for the bared end 26 of the lead wire against which it is clamped by the free end portion of the shank 39 of the screw. It is also preferred to extend this wall 43 backwardly beyond the end of the shank of the screw and form it into a substantially cylindrical portion 45, into which the bared end 26 of the wire is inserted and by which the bared wire is guided to the clamping position between the shank 39 of the screw and the inclined surface 44. This tubular portion also acts as a support for the wire and prevents its being shifted laterally out of position by pressure of the screw. As this tubular portion extends below the rear face of the section 31 of the body, the rear section 30 of the body is provided with a recess 46 to receive this section, and the section 30 is also provided with an opening 47 leading from its rear wall to the terminal recess and in substantial alignment with the inclined surface 44, so that the lead wire may be inserted from the rear for back wiring. The base portion 37 may also be provided with an opening 48 also in substantial alignment with the inclined surface 44 to permit insertion of the bared end of the lead wire from the front to the clamping position for front wiring if desired, similar to the arrangement shown at the left end of Fig. 2. It will be seen that this arrangement provides for both front and back wiring without the necessity of wrapping the lead wire around the screw under its head, but if desired the wire may be so wrapped around the screw and clamped in the usual way.

Fig. 8 shows a slightly different construction. In this arrangement, the terminal connection is substantially the same as that shown in Figs. 3 and 4, except that the tubular extension 45 is omitted. In other words, the inclined wall 44 is cut off at about the level of the dividing surface 49 between the two sections 30 and 31 of the body, but it has the inclined clamping surface 44 curved laterally and arranged adjacent to the shank 39 of the screw, so that the bare wire 26 is clamped between the shank of the screw and the inclined surface 44, the same as in the arrangement of Fig. 3. The rear section 30a of the body is provided with a tapered opening 50 in alignment with the inclined surface for insertion of the lead wire from the back or rear of the device to the clamping position, and for guiding it to this position. The base portion 37 of the terminal may also be provided with the opening 48 in substantial alignment with the inclined surface 44 so

that the lead wire may be inserted from the front for front wiring, as described in connection with Fig. 3. In this form also, of course, the lead wire may be wrapped around the screw under the head and clamped in the usual manner, if that form of connection is preferred.

It will be seen from the above that in each of the various arrangements shown, both back and front wiring are provided without requiring the wrapping of the bared wire around the screw under its head, but, however, that this method of connection may be employed if desired. Also that, although the wire is not wrapped around the screw, it is effectively clamped and held and provides a very effective electrical connection. The wire may be set and clamped by merely inserting it to the clamping position and then setting up the screw, and it may be as easily and quickly detached if desired. With this arrangement, after the wire is clamped there is no loose end to contact other elements and form short circuits, as may often happen where the wire is wrapped around under the head of the screw, and also bending or shifting of the wire leading to the device does not loosen the binding screw, as is often the case where the wire is wrapped around the screw.

Having thus set forth the nature of my invention, I claim:

1. A wire terminal connection for electrical wiring devices including a body of insulating material provided with a recess having inclined surfaces, a terminal mounted in said recess comprising a base portion and side walls at opposite edges of the base portion, one edge of each side wall being inclined to seat on the inclined surfaces of the recess, a binding screw threaded in the base portion and including a shank between said side walls, another wall extending rearwardly from the base between the side walls and provided with a laterally curved surface at one side of the shank and inclined to the axis of the shank in position to support a lead wire clamped between the shank and said surface, and said body including a separate member over the open side of the recess to retain the terminal therein and provided with an opening leading from its rear wall to the recess for insertion of the bared end of a lead wire to the clamping position.

2. An electrical wiring terminal connection comprising a metal plate forming a base portion and provided with a threaded opening there-

through, a binding screw threaded into said opening in the base portion including a head on one side of said base and a shank extending from the other side of the base, an integral wall extending in the same direction as the shank from one edge of the base portion at one side of the shank of the screw and inclined to the axis of this shank, said wall being provided with an inclined surface at one side of and adjacent the shank between which the bared end of a lead wire may be clamped, and said inclined wall being provided with a tubular extension at its free end in substantial alignment with said inclined surface to guide the lead wire to clamping position.

3. A wire terminal connection for electrical wiring devices including a body of insulating material provided with a recess, a terminal mounted in said recess comprising a base portion in the form of a metal plate provided with a threaded opening therethrough and side walls at opposite edges of the base portion integral therewith cooperating with walls of the recess to position the terminal therein, a binding screw threaded into said opening in the base portion and including a shank extending inwardly between the side walls, an integral inclined laterally curved lead wire supporting wall extending inwardly from another edge of the base portion to a position at one side of the shank, and said latter wall being located adjacent to the shank and inclined to the axis thereof to support a lead wire clamped by said shank against said wall.
